UNITED STATES PATENT OFFICE.

THOMAS G. G. MOUAT AND LEE BURT, OF DETROIT, MICHIGAN.

WATER-HEATER.

SPECIFICATION forming part of Letters Patent No. 408,893, dated August 13, 1889.

Application filed June 1, 1889. Serial No. 312,891. (No model.)

To all whom it may concern:

Be it known that we, THOMAS G. G. MOUAT and LEE BURT, citizens of the United States, residing at Detroit, county of Wayne, State of Michigan, have invented a certain new and useful Improvement in a Hot-Water Heater; and we declare the following to be a full, clear, and exact description of the invention, such as will enable others skilled in the art to 5 which it appertains to make and use the same, reference being had to the accompanying drawings, which form a part of this specification.

Our invention relates to certain new and 15 useful improvements in hot-water heaters, and has reference more particularly to improvements in the line of such heaters as that embodied in the pending application of Thomas G. G. Mouat, Serial No. 303,391, 20 wherein a series of sections extending across the combustion-chamber of a furnace communicate, intermediate their extremities, with a water-chamber above said chamber provided with drop-tubes, all as more fully 25 explained in said application.

The objects of our present invention contemplate, first, the provision of separate water-chambers communicating, respectively, with separate sections beneath and provided 30 with drop-tubes, as hereinafter set forth; second, the construction and union of the respective sections and their communicating water-chambers in such a manner that each section, with its connected chamber and drop-tubes, may be separable from the remaining 35 series of sections and chambers, so that each section, with its corresponding chamber, may be independently removed or united with the remainder; third, the construction of the 40 said sections with flanges to meet together and compel the products of combustion to pass laterally from the combustion-chamber and thence upward over the sections and about the marginal as well as the central 45 drop-tubes to more perfectly insure the proper distribution of heat over and about all parts of the heater; fourth, the independent construction and arrangement of the 50 separate sections and separate communicating chambers in such a manner that the heat therefrom may be led independently to any

desired part of the building to be heated; fifth, to provide a novel hot-water heater wherein the production of steam is rendered impossible. Our invention, sixth, also contemplates the general construction, combination, and arrangements of devices and appliances, more fully hereinafter described and set forth in the claims, and more explicitly illustrated in the accompanying drawings, in 55 which—

Figure 1 is a vertical section of a device embodying our invention. Fig. 2 is also a vertical section of the same at right angles to that shown in Fig. 1. Fig. 3 is a perspective showing two sections and their communicating chambers constructed to deflect the products of combustion to the sides of the combustion-chamber.

We carry out our invention as follows: 70

A denotes any suitable inclosing-wall of a furnace; B, any suitable grate in the combustion-chamber of the furnace.

C represents a water-section extending across the combustion-chamber, preferably 75 rising toward the center of the section, although we do not confine ourselves to this construction.

C' denotes an inflow-pipe communication with each section, and C² a return-pipe. The 80 inflow-pipes and return-pipes may lead from a common header or manifold, as shown at C³ and C⁴, respectively.

D is a water-chamber located above a corresponding section C and communicating 85 therewith through one or more pipes E, leading upward from the said section intermediate its ends, the construction and arrangement being such that water entering the section will in all cases be compelled to pass to 90 the center of the section, and thus over the middle of the fuel-bed, so as to receive the greatest degree of heat before it can find its passage upward therefrom. The pipes E, thus arranged, lead to the chamber D above intermediate of its extremities. The individual chambers are provided with a series of drop-tubes F, communicating therewith and also with exit-pipes G G', preferably located at or 95 near the extremities of said chambers, as 100 shown, so as to compel the water entering the chamber through the pipe E at the middle of

the chamber to pass first to the extremities of the chamber before it can pass to the line-pipes therefrom, thus causing the drop-pipes to be always filled, and compelling an efficient circulation of the water and the retention of the same over the fuel-bed for the longest practicable period in order to be most thoroughly heated thereby.

The exit-pipes from the water-chambers D, where a series of them are employed, may, if desired, be engaged with a common manifold, as at II' II'', at each end of said chambers; or the said exit-pipes may separately lead to a special circuit. We contemplate either of these methods of communicating the chambers with the line-pipes, as may be preferred, as coming within the scope of our invention. We prefer also to construct or provide the separate sections with flanges or ribs c to close up the space between the upper edges of the sections and so compel the products of combustion to pass to the extremities of the sections in order to find their escape upward; or, instead of so constructing the sections with flanges c for this purpose, the individual chambers may be provided with a flange d, to close the space between the upper adjacent edges of the chambers and so compel the products of combustion to pass to the extremities of the chambers before finding their exit from the combustion-chamber, and consequently causing the heat to be distributed in an efficient manner throughout the combustion-chamber and about all parts of the apparatus. Should the sections be provided with said flanges, the chambers may be constructed without them, and vice versa; or the flanges may be altogether omitted without departing from our invention.

In a heater constructed in this manner it is evident that the water must at all times cover every part of the heater from its entrance into the sections C to its exit through the outlet-pipes at the extremities of the chambers D, and so that when the water is in circulation the formation of steam is effectually prevented. It is obvious also that the water from any chamber of the series may be led to any special circuit of the line-pipes desired. The water being independently heated in the separate sections and communicating chambers may be also independently distributed. In this manner the heat may be effectually distributed to every part of the house. The water from any given chamber returning to the manifold C' has its temperature raised before its entrance again into the heater.

What we claim as our invention is—

1. In a hot-water heater, the combination, with an individual section C, extending across the combustion-chamber, of an individual water-chamber D, provided with outlets to the line-pipes and communicating with said section intermediate the extremities of said section, said section and communicating chamber independently removable from the heater, substantially as set forth.

2. In a hot-water heater, the combination, with an individual section C, extending across the combustion-chamber, of an individual water-chamber D, provided with drop-tubes and outlets to the line-pipes and communicating with said section intermediate the extremities of the section, said section and communicating chamber independently removable from the heater, substantially as set forth.

3. In a hot-water heater, the combination, with an individual section C, extending across the fuel-bed, of an individual water-chamber D, communicating therewith, the one provided with flanges to deflect the products of combustion, the other open at its sides to allow the passage of the products of combustion, substantially as set forth.

4. In a hot-water heater, the combination, with a series of individual sections C, of a series of individual water-chambers D, each communicating with a corresponding section, each section with its chamber separable from the remaining sections and chambers of the series, substantially as set forth.

5. In a hot-water heater, the combination, with a series of individual sections C, extending across the combustion-chamber, of a series of individual water-chambers D, each communicating independently with a corresponding section, said chambers provided with drop-tubes and outlet-pipes leading from the extremities of said chambers, substantially as set forth.

6. In a hot-water heater, the combination, with a series of individual sections C, of a series of individual water-chambers D, each communicating, respectively, with a corresponding section, outlet-pipes leading from said chambers, each chamber connecting with separate circuits, substantially as set forth.

In testimony whereof we sign this specification in the presence of two witnesses.

THOMAS G. G. MOUAT.

LEE BURT.
